CLAMP FOR CLOTHES HANGERS, DISPLAY BOARDS, OR SIMILAR APPLICATIONS

Herb Coon, New York, N.Y., assignor to Hercules Clip Corporation, New Hyde Park, N.Y., a corporation of New York

Filed Sept. 13, 1967, Ser. No. 8,585

Term of patent 14 years

(Cl. D49—1)

FIG. 1 is a perspective view of a clamp for clothes hangers, display boards, or similar applications showing my new design;

FIG. 2 is a front view thereof;

FIG. 3 is a side view thereof as seen looking from the left of FIG. 1;

FIG. 4 is a top view thereof as seen looking down at FIG. 1; and

FIG. 5 is a bottom view thereof as seen looking upward at FIG. 1.

I claim:

The ornamental design for a clamp for clothes hangers, display boards, or similar applications, as shown.
